Primary Examiner — Jack Reickel*Assistant Examiner* — Sydney M Evans(74) *Attorney, Agent, or Firm* — Lee & Hayes, P.C.(57) **CLAIM**

The ornamental design for a wheel assembly lock key, as shown and described.

DESCRIPTION

FIG. 1 is a top, front, right-side perspective view of a wheel assembly lock key, showing my new design;

FIG. 2 is a back, bottom, right-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a front, top perspective view of the lock key attached to a disclaimed wheel assembly; and,

FIG. 10 is a front, bottom perspective view thereof.

The dashed broken lines depict portions of the wheel assembly lock key and environmental context of the wheel assembly that form no part of the claimed design.

1 Claim, 10 Drawing Sheets(56)
